POCKET PURSE ASH TRAY

Art F. Kissner, Jr., Williston Park, N. Y.

Application May 2, 1947, Serial No. 745,534

3 Claims. (Cl. 206—37)

1

This invention relates to ash trays and more particularly to an ash tray which may be carried in a lady's purse.

It is an object of the present invention to provide an ash tray of small dimension which has an opening into which ashes can be deposited and wherein by the rotation of a sleeve cover the opening can be closed.

Another object of the present invention is to provide an ash tray suitable for use in a lady's purse and which has a handle which can be extended from the same and through which a finger can be extended to support the ash tray in a convenient position to receive the ashes.

According to the invention, there is provided a sleeve which is open at one end and which has a hole in its wall for receiving ashes. This sleeve has an end plate at one end on which there is secured a handle of ring formation which is adjustable radially outwardly to receive a finger of the smoker from which the tray can be supported. Into the sleeve there is extended a closure sleeve also having an opening and an end plate and which closure sleeve is connected to the first sleeve for rotatable adjustment. An annular groove is provided in one sleeve to receive a screw projecting from the other sleeve so as to prevent the axial displacement of the sleeves. Upon removing the screw, the sleeves may be disassembled so that they may be more easily cleaned.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a perspective view of an ash tray supported upon a finger with the closure sleeve adjusted to the open position and the tray made ready for use.

Fig. 2 is an end elevational view of the ash tray with the supporting handle moved to its retracted position.

Fig. 3 is a top plan view of the ash tray.

Fig. 4 is a transverse cross sectional view taken on the line 4—4 of Fig. 3.

Fig. 5 is a cross sectional view, in elevation, taken substantially on the line 5—5 of Fig. 2.

Fig. 6 is an enlarged transverse cross sectional view similar to Fig. 4 with the closure sleeve moved to its closed position.

Fig. 7 is a perspective view of a modified form

2 of the invention wherein the ring serves to lock the sleeves in their closed positions.

Fig. 8 is a top plan view of the ash tray shown in Fig. 7.

Fig. 9 is an end view with the retaining ring in place.

Fig. 10 is a cross sectional view taken on line 10—10 of Fig. 8.

Fig. 11 is a cross sectional view taken substantially on the line 11—11 of Fig. 9.

Fig. 12 is a view similar to Fig. 10, but showing a different position of the parts.

Fig. 13 is an enlarged detailed view of a portion of Fig. 11, but showing a different position of the parts.

The pocket ash tray, according to the present invention, includes an outer sleeve or casing 10 having an end plate 11 thereon. This sleeve has an opening 12 therein through which ashes may be deposited in the tray. Rotatable within the outer casing 10 there is a concentric inner sleeve or casing 13 having an opening 14 adapted to be aligned with the opening 12 of the outer casing 10. This inner sleeve 13 has an end plate 15 and an external annular groove 16 adjacent the end plate 15. The outer casing 10 has a screw 17 which extends into the groove 16 to retain the parts against axial displacement. On the end plate 11, there is a ring 18 which can be adjusted radially outwardly to the position shown in Fig. 1, so that a finger 19 can be extended through the same to support the ash tray in the hand. When the ring member 18 is not in use, it can be rotated on its attaching screw 21 to the position shown in Fig. 2 over the end plate 11. The opening 14 in the closure 13 extends to the edge thereof, as indicated at 23, to provide a slot through which the screw 17 can be relieved from the groove 16 whereby the parts can be separated from each other. The end plates 11 and 15 are of such diameter that they provide a grip for the fingers to effect the turning of the sleeves relative to one another.

Referring now to the form of the invention shown in Figs. 7 to 13, the end plate 11 of the ash tray having the ring 18 is provided with a recess 26 having a cam portion 27, see Figs. 11 and 13, thereon over which ring 18 will be projected as the ring 18 is turned out of the recess 26 whereby to cause outward movement of a pin 28 on which the ring 18 is rotatably mounted. Pin 28 extends slidably but non-rotatively through the end plate 11 and has a radially extending arm 31 on its inner end which is formed at its free end with a wide portion 32 which engages between

spaced projections 33 formed within the sleeve 13 for retaining the sleeves 10 and 13 in a closed position in which the openings 12 and 14 are disaligned, see Fig. 12. An expansion spring 34 on the pin 28 operates between the adjacent faces of the end plate 11 and the arm 31 retaining the arm 31 in a position in which its wide portion 32 is engaged between the projections 33. As the ring 18 is pivoted, it will ride upon the cam surface 27 out of the recess 26. While the ring 18 is in the recess 26, it is locked against easy displacement by the spring 34.

As the ring 18 is rotated, it moves up on the cam surface 27 drawing axially outward on the pin 28 against the action of the spring 34 withdrawing the wide portion 32 from between the projections 33 to a position alongside the projections 33, see Fig. 13, freeing the sleeves 10 and 13 to be rotated relative to each other to align the openings 12 and 14, as shown in Fig. 10. In order to insure realignment of the arm 31 with the space between the projections 33, when the sleeves are rotated in a direction to disalign the openings 12 and 14, the outer sleeve 10 is formed with an elongated slot 37 and a set screw 36 passes freely through the elongated slot 37 and threadedly engages the inner sleeve 13 to limit relative rotation of the sleeves to the length of the slot 37. The length of the slot 37 is such as to limit rotation of the sleeves 10 and 13 between positions in which the arm 31 is aligned with the space between the projections 33, see Fig. 12, or in which the openings 12 and 14 are aligned, as shown in Fig. 10.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. An ash tray comprising rotatively interengaged sleeves, and plates closing the opposite ends of said sleeves and forming grips for relatively rotating said sleeves, said sleeves being formed with openings alignable with each other in a certain relative rotative position of said sleeves to permit ashes to be passed therethrough, and means for locking said sleeves against relative rotation in the position of said sleeves in which their openings are disaligned, said locking means comprises spaced projections within one of said sleeves, a pin axially slidably mounted on the end plate of the other of said sleeves, a recess formed in the outer face of the said end plate, a handle rotatively mounted on the outer end of said pin and normally disposed within said recess, an arm radially mounted on the inner end of said pin and having its free end disposed within the space between said projections holding said sleeves against relative rotation when said handle is in said recess, and resilient means retaining said pin in an axial position relative to said end plate in which said handle is in said recess and said arm has its free end between said projections.

2. An ash tray comprising rotatively interengaged sleeves, end plates closing the opposite ends of said sleeves and forming grips for relatively rotating said sleeves, said sleeves being formed with openings alignable with each other in a certain relative rotative position of said sleeves to

permit ashes to be passed therethrough, and means for locking said sleeves against relative rotation in the position of said sleeves in which their openings are disaligned, said locking means 5 comprises spaced projections within one of said sleeves, a pin axially slidably mounted on the end plate of the other of said sleeves, a recess formed in the outer face of the said end plate, a handle rotatively mounted on the outer end of said pin and normally disposed within said recess, an arm radially mounted on the inner end of said pin and having its free end disposed within the space between said projections holding said sleeves against relative rotation when said handle is in said recess, and resilient means retaining said pin in an axial position relative to said end plate in which said handle is in said recess and said arm has its free end between said projections, said recess being surrounded by a cam surface, whereby the act of rotating said handle about the outer end of said pin will cause said handle to ride up on said cam surface to draw outward on said pin against the action of said spring to withdraw the free end of said arm from between said projections 20 freeing said sleeves to be rotated relative to each other.

3. An ash tray comprising rotatively interengaged sleeves, end plates closing the opposite ends of said sleeves and forming grips for relatively 25 rotating said sleeves, said sleeves being formed with openings alignable with each other in a certain relative rotative position of said sleeves to permit ashes to be passed therethrough, and means for locking said sleeves against relative 30 rotation in the position of said sleeves in which their openings are disaligned, said locking means 35 comprises spaced projections within one of said sleeves, a pin axially slidably mounted on the end plate of the other of said sleeves, a recess formed in the outer face of the said end plate, a handle rotatively mounted on the outer end of said pin and normally disposed within said recess, an arm radially mounted on the inner end of said pin and having its free end disposed within the space between said projections holding said sleeves against relative 40 rotation when said handle is in said recess, and resilient means retaining said pin in an axial position relative to said end plate in which said handle is in said recess and said arm has its free end between said projections, one of said sleeves being formed with an elongated slot, and a set screw passing freely through said elongated slot and threadedly engaging the other of said sleeves limiting relative rotation of 45 said sleeves to positions in which said openings are aligned or in which the free end of said arm is aligned with the space between said projections.
